UNITED STATES PATENT OFFICE.

JOHN B. BRAY AND OTIS S. PIERCE, OF PAWTUCKET, RHODE ISLAND.

MACHINE FOR DYEING YARN ON THE SKEIN.

SPECIFICATION forming part of Letters Patent No. 402,648, dated May 7, 1889.

Application filed October 20, 1888. Serial No. 288,717. (No model.)

To all whom it may concern:

Be it known that we, JOHN P. BRAY and OTIS S. PIERCE, citizens of the United States, residents of Pawtucket, in the county of Providence and State of Rhode Island, have invented certain new and useful Improvements in Machines for Dyeing Yarn on the Skein, of which the following is a specification.

10 Our improvements relate to machines of this class by means of which the work can be more expeditiously done at a great saving of time and labor, and in which a more thorough saturation of the yarn is secured, and these 15 objects we accomplish by the mechanism illustrated in the accompanying drawings, in which—

Figure 1 is a side elevation of the machine, the broken part exhibiting a perspective 20 view of the interior; Fig. 2, a front elevation of two reel-frames, in perspective, on the shaft; Fig. 3, a side elevation of keir and brake; Fig. 4, the perforated reel-stick; Fig. 5, a cross-section of reel-stick and disk; Fig. 6, a 25 cross-section of side arm of reel-frame and screw; Fig. 7, a view of reel-frame in detail; Fig. 8, a detail view of one-half of reel-frame for the side arm with the cap open; Fig. 9, a longitudinal section of side arm of reel-frame; Fig. 10, a detail view of the other half of 30 side arm for reel-frame with the cap open; Fig. 11, a longitudinal section of hub and spoke; Fig. 12, a cross-section of hub and shaft.

35 Similar letters refer to similar parts throughout.

In the drawings, A designates the keir, solidly constructed of wood or other suitable material, having an outside length, say, of ten 40 feet, a width, say, of four feet, and a depth, say, of five feet, with an interior dimension for any required quantity of dyeing or coloring matter.

B designates a solid substantial frame having the supporting-legs b b' and a solid cross-piece, b².

C designates a journal-box firmly secured to the frame-work and bearing the shaft D of the wheel. This shaft may be connected with 50 any proper system of gearing which will impart a rotary motion to the shaft for a certain number of revolutions in one direction and

then a reverse rotary motion in the opposite direction. A similar journal box and bearing is provided for the opposite end of the 55 shaft D on the opposite vertical post of the frame. Upon either end of the shaft and within the side walls of the keir are secured the flanged hubs E, revolving with the shaft.

The hubs are constructed of metal, (see 60 Figs. 11 and 12,) with a broad flange. e, e', and e² are ridges upon the inner surface of this flange, extending from the periphery to the axis of the hub, these ridges making a groove, into which the shoulder of the spoke 65 fits. Forty of these ridges, forming twenty such grooves, we would prefer to construct.

F (see Fig. 11) designates one of a series of twenty spokes, preferably, for each hub, constructed of metal, with the longitudinal slot f 70 extending from the end to the shoulder. The end of this spoke is hollowed out to form a bearing for the shaft of the reel-stick. Upon this spoke is constructed (see Fig. 11) a lock to hold the upper reel-stick in the bearing 75 of the spoke.

g designates an arm swinging loosely upon the pin g², securing the same to the spoke and bent to cover over the hollow made in the end of the spoke to form a bearing, as 80 described.

i represents a pin mounted vertically in a recess of the head upon a spiral spring. i' designates a shaft secured to this pin and extending from the recess through a slot to the 85 outside of the head. This pin fits into a hole in the bent end of the swinging arm and holds the same securely over the hollow bearing. To unlock this arm, it is merely necessary to press down the pin by means of the 90 shaft i'.

The shoulder j of the spoke fits into the groove formed by the ridges of the hub-flange, and is firmly secured on the flange by bolts.

H (see Fig. 7) designates a reel-frame, 95 consisting of four parts, which are described in detail as follows:

In the drawings, (see Fig. 4,) I designates the upper reel-stick, constructed of metal or other suitable material, with concave or fluted 100 sides, as shown by the cross-section, (see Fig. 5,) this construction being employed so that the skein may only rest upon the edges of the stick, leaving an air-space between the yarn

and the main part of the stick. Through the shaft of the stick are drilled the longitudinal perforations a , a , &c., extending entirely through the metal and forming in the interior of each stick two hollows. This construction is followed in each of the reel-sticks, and allows the unrestricted percolation of the dyeing-liquor through that portion of the skein resting upon the sticks.

10 N designates a friction-disk, mounted on the end of the shaft J of the upper reel-stick. (See Fig. 1.) This disk is mounted on the extreme end of the shaft, which is extended beyond the stick for this purpose.

15 y designates a rubber bunter secured to the under side of the cross-beam of the frame in such a position as to collide with the disk when the revolution of the shaft brings the reel-stick beneath the said cross-beam. We prefer this form of mechanism for imparting part of a revolution to the upper reel-stick, since the distance through which the yarn is to be moved is of necessity very slight, and this form of mechanism imparts a very gentle motion and occasions no displacement of the skeins.

20 The side arms of the reel-frame are constructed as follows, (see Figs. 7, 8, and 9:) Each side arm consists of two adjustable parts.

25 In Fig. 8 s designates a longitudinal slotted aperture.

30 i' and i^2 designate slotted grooves, the groove i' of the cap closing over the groove i^2 when the cap is locked, as hereinafter described.

35 e^3 and e^4 are apertures having a corresponding thread, through which a screw passes to hold the cap securely locked upon the arm.

40 h designates a hinge for the cap.

45 In Fig. 10 i^3 and i^4 are corresponding slotted grooves, e^5 and e^6 corresponding threaded apertures, and d a threaded aperture in the arm. In Fig. 9 these two sections appear in position with the caps locked and the arms secured for any desired length of reel by means of the thumb-screw k , which locks the longitudinally-slotted arm by means of the threaded aperture d in the corresponding section. A like description applies to each one of the arms of the several reels. When the length of these arms is properly adjusted, the shafts of the upper and lower reel-sticks are locked by means of the caps into the bearings formed by the slotted grooves i' , i^2 , i^3 , i^4 , and the entire reel, Fig. 7, slides into the slot f of the spoke F , (see Fig. 11,) which is firmly secured to the hub E , as described.

55 The skeins of yarn to be dyed are set upon the reel-sticks, the distance between which is adjusted to allow the yarn to hang somewhat loosely, and the reel-frame then introduced into the slotted spoke F . The arm g' is then locked, as described, and the reel-frame is then held firmly in position on the slotted spoke.

60 When the machine has been loaded to the

desired capacity, motion is imparted to the main shaft and the reel-frames containing the yarn are plunged into the dyeing or coloring matter contained in the vat or keir and emerge on the other side. As the upper reel-stick, which, as described, is provided with a friction-disk, reaches a position under the cross-bar of the supporting-frame, the disk comes in contact with a rubber bunter secured to said cross-bar and extending downward far enough to engage with the surface of the disk, and causes the reel-stick to make part of a revolution, and brings a new part of the skein in contact with the edges of the stick. When the yarn on the reel-frame has been plunged into the liquor any required number of times, the motion of the shaft is reversed and the opposite side of the skein plunged first into the bath, thus distributing the coloring-matter more evenly. We desire to call attention to our method of introducing liquor into the tank while the shaft is in motion.

65 One end of the tank or keir (see Fig. 1) is constructed with double walls and an air-space between the outer and inner wall extending to the bottom of the keir. Between the bottom of the keir and the lower edge of the inner wall a space is left extending the width of the keir, thus forming an unobstructed channel communicating with the outside. If, in the process of dyeing, it becomes necessary to change the shade of the coloring-matter already in the keir, additional liquor may be poured into this channel, and when the shaft revolves in the direction indicated by the arrow-head it will readily be seen that a current will be formed which will draw in the additional coloring-matter and thoroughly mix the same with that in the keir. This construction obviates the necessity of injecting the additional liquor by force.

70 In Fig. 3 is shown our contrivance for holding the wheel locked while loading the reels upon the spokes.

In the drawings, P designates a cog-wheel mounted upon the shaft D .

75 R designates a lever swinging loosely upon the pin r ; Q , a straight arm secured to the lever, moving forward and back by means of the guiding-slot w and two pins, w' and w^2 . This lever engages with the gear P by the point q , and holds the shaft firmly locked.

80 S designates a spiral spring, and t a loose arm swinging upon a pin. When the lever is pulled back, this pin drops over the projecting lip v of the arm Q , and holds the point of the arm away from the gear, allowing the shaft to revolve. By lifting up this loose arm the spiral spring will cause the arm Q again to engage with the gear.

85 We are aware that previous to this application machines for dyeing yarn on the skein have been employed, as by Letters Patent issued to Charles L. Klauder, dated February 7, 1888, No. 377,393, for a "dyeing and scouring machine;" but the advantages in

our machine as constructed and described are, that by employing a reel-frame separate and distinct from the supporting arms or spokes, adjustable to any length of skein and contrived to slide into a groove of said spokes, the yarn can be loaded and unloaded away from the machine, and thus more expeditiously and securely handled; that the capacity of our machine, using a comparatively equal size of 5 keir and shaft, will be much greater for holding yarn, since as the loading and unloading are done off the machine the supporting arms or spokes can be placed more closely together on the shaft, thus allowing the use of a much 10 larger number of reels; that a more perfect adjustment is secured by our machine in the construction as employed; that by the use of a perforated hollow reel-stick a more complete saturation of that part of the skein 15 resting upon the stick by the liquor is secured, which would do away with any absolute necessity of employing mechanism for changing the position of the skein on said sticks when in the process of dyeing, although in our machine we have described such means; that, owing to the reverse motion applied to our 20 shaft, both sides of the skein can be alternately plunged into the coloring-bath, and thus a more perfect saturation secured in a shorter space of time; and, again, additional liquor can at any time be added to that in the 25 vat without any means for injecting the same.

We claim that in machines as at present constructed it is necessary, in the process of 30 loading and unloading, to employ at least two men, or a man and a boy; but in our construction one man or one boy can easily load or unload the machine and attend to the same during the entire process of dyeing. In dyeing 35 yarn without a machine the services of two men are always required.

What we claim as new, and desire to secure by Letters Patent, is—

1. In a machine for dyeing yarn on the skein, the combination, substantially as hereinbefore 45 described, of a tank containing dye or liquor, a frame secured thereto supporting a journal-box, a rotary central shaft alternately rotating in either direction, flanged hubs mounted upon the said shaft, longitudinally-slotted 50 spokes secured to said hubs, a frame for holding the skeins of yarn fitting into the slotted groove of said spokes, and means for locking said frame into said spokes.
2. In a machine for dyeing yarn on the 55 skein, the combination, substantially as hereinbefore described, of a tank, a frame secured thereto, a rotary shaft, flanged hubs, longitudinally-slotted spokes, means for holding said shaft and spokes while in the process of 60 loading and unloading, a frame for holding the skeins, adjustable for any length of skein, fitting into the slotted groove of the spokes, means for locking said frame into said spokes, and a friction-disk, N, mounted upon the ex- 65 tended shaft J of the upper reel-stick of the frame colliding with a bunter extending downward from the cross-bar of the supporting-frame.
3. The combination, in a dye or liquor tank, 70 of a tank, a rotary shaft, flanged hubs secured thereto, longitudinally-slotted spokes secured to said hubs, and a frame for holding the skeins of yarn, having side arms formed of corresponding strips of metal slotted and adjustable to each other for any length of skein, 75 fitting into the groove of said spokes and securely locked in said spokes by the swinging arm g, which fits by means of the hole in its bent end upon the pin i.

JOHN P. BRAY.
OTIS S. PIERCE.
